MARC RESEK, OF CLEVELAND HEIGHTS, AND JOHN ALGER DAHLSTROM, OF EAST CLEVELAND, OHIO, ASSIGNEES TO PERFECTION STOVE COMPANY, OF CLEVELAND, OHIO, A CORPORATION OF OHIO.

OIL-BURNING APPARATUS.

Application filed June 24, 1925. Serial No. 39,236.

This invention relates to improved oil burning apparatus that is characterized by means for varying the oil level with respect to the burner thereby to control the size of 5 the flame and consequently the heat produced by the apparatus.

In the present preferred form of the invention, a burner of the injector type is employed and it is actuated by fluid having a 10 substantially constant pressure; and the oil level in the burner is governed by thermostatically controlled mechanism thereby to change the heat produced by the burner according to the changes in temperature affecting the thermostat.

In a more complete embodiment of the invention, a plurality of burners are employed, and certain ones of these are thrown into and out of operation successively as the demand 20 for heat increases and decreases.

However, in more general terms, the invention may be defined as consisting of the combination of elements set out in the claims annexed hereto, and the main objects sought to 25 be attained may be enumerated as follows:

To provide a highly efficient oil burning apparatus that is economical from the standpoint of fuel consumption and is automatic of operation and is thoroughly reliable;

To provide oil burning apparatus in which the flame is controlled by varying the oil level with respect to the burner and preferably to employ automatic means for effecting changes in the oil level;

To provide a thermostatic control for the automatic means whereby the temperatures affecting the thermostat determine the output of heat by the apparatus;

To provide, in oil burning apparatus, a 40 tank, a reservoir to which oil is pumped from the tank, the reservoir supplying fuel to the burner and having an overflow of variable height which returns excess fuel to the tank, and automatic means for changing the elevation of the overflow thereby to control the burner flame;

To provide in apparatus of the character 50 immediately above described, a burner of the injector type, and a steam generator for supplying the actuating fluid for the burner, together with a steam pump operated by steam from the generator for circulating the fuel through the reservoir from the tank; and

To provide in apparatus of the character

aforesaid one or more auxiliary burners that 55 is or are automatically thrown into operation as the temperature affecting the thermostat drops below a predetermined value and is or are thrown out of operation when the temperature resumes this predetermined 60 value, the means for accomplishing this result being under the control of the mechanism for varying the fuel level.

Referring now to the accompanying drawings which constitute a part hereof and 65 wherein similar reference characters designate corresponding parts throughout the several views, Fig. 1 is a front elevation of an oil burning apparatus embodying our invention; Fig. 2 is a transverse section through 70 the apparatus on the line 2—2 of Fig. 4; Fig. 3 is a right hand side elevation of the apparatus; Fig. 4 is a central longitudinal section through the apparatus as though viewed from the side opposite that from which Fig. 3 is 75 taken; Fig. 5 is an enlarged vertical section through the control valves of the auxiliary burners and through the oil reservoir with its variable overflow and the mechanism for adjusting said overflow, the view being taken on the line 5—5 of Fig. 3; Figs. 6, 7, 8 and 9 are sections on the respective correspondingly numbered section lines of Fig. 5; Fig. 10 is a plan view of the oil reservoir and mechanism shown in Fig. 9; Figs. 11 and 12 are views at 80 right angles to each other of one of the pawl carrying plates included in the mechanism of Fig. 9; Figs. 13 and 14 are a side elevation and a plan, respectively, of one of the pawls of said mechanism; Fig. 15 is a wiring diagram of the electric circuit through which 85 the mechanism controlling the oil level of the reservoir is automatically governed by a thermostat; Fig. 16 is a diagrammatic representation of a modification of the invention; and Fig. 17 is a sectional side elevation of a 90 further modification.

The oil burning apparatus is intended for use in conjunction with house heating and other furnaces and is designed to be positioned in front of a door of the furnace, as in 100 front of the ash pit door (the regular coal burning grates being removed) so that the products of combustion from the apparatus are projected into the fire box for heating the furnace. In Figs. 3 and 4 a portion of a furnace is shown, the same being designated A, 105 and, as revealed in the sectional view of Fig.

4 its front wall is provided with an opening *a* through which the products from the combustion chamber of the apparatus are projected into the fire box *a'*. The furnace may be of
5 the steam boiler, hot water, or hot air class; and it may be explained at this time that our invention is applicable to many other purposes than to the operation of heating plants of the classes mentioned.

10 Our improved oil burning apparatus, designated generally by the reference numeral 1, is supported upon legs 2, and it comprises a metallic box like casing 3 to one side of which is hinged, as at 4, a cover 5. Disposed transversely of the bottom portion of the casing 3 is a preheating burner 6, the same being shown as in the nature of a basin into which a quantity of liquid fuel may be introduced through a filling spout 7 (Figs. 1 and 2), air 15 to support combustion being admitted through a passageway 8 and a series of tubular bosses 9 which project above the surface of the oil. An opening 10 in the side of the structure gives access to the preheating burner 20 for lighting purposes and this opening is normally closed by a door 11 having an extension 25 12 for covering the filling spout 7. Where gas is available, a gas preheating burner may be substituted for the one above described.

30 The lower portion of the casing 3 is lined with suitable refractory material 15 which encloses a combustion chamber 16 that communicates at its rear end with the fire box a' of the furnace A. A passageway 18 opens through
35 the roof of the combustion chamber into a compartment 20 the top of which is formed by a shell 21 that is shown as spaced from and secured to the cover 5, as by bolts 22. If desired, the space between the shell and cover
40 may be filled with suitable heat insulating material. At its rear end, the compartment 20 communicates with the interior of the furnace through the top portion of the opening a .

The upper end of the passageway 18 is surrounded by a metal frame 23. A bead 24 extends about the upper side of this frame and is spaced a suitable distance from the edge thereof, and adapted to rest upon the frame, inwardly of the bead 24, is a damper 25. This damper is made up of a metal frame 26 that carries a body of refractory material.

55 Situated within the rear end of the compartment 20, where it may be exposed to the products of combustion escaping through the passageway 18 from the combustion chamber, when the damper 25 is open, is a steam generator 28, shown as provided with heat abstracting vanes 29. The generator is closed at one end, and at the other is flanged (Fig. 2) for 60 connection with a float chamber 30 which has a removable cover 31 that is shown as held in place by screws 32 which bind the peripheral flanges of the chamber and cover together. Water is admitted to the float chamber and to 65 the generator through a pipe 35 and is main-

tained at a substantially constant level therein by a suitable valve (not shown) that is controlled by a float 36 that occupies the float chamber.

The end wall of the steam generator 28 opposite the float chamber 30, is provided adjacent its top with a hollow boss 40 and adjacent its lower edge with a similar boss 41. A nipple 42 is screwed into the boss 40 and at its outer end carries a steam dome 43. Steam is led from the steam dome through pipes 44, 45 and 46 (Fig. 3) to the middle section 50 of a multiple oil burner designated generally by the reference numeral 51. Each section of this burner is constructed, as shown in Fig. 4, of a steam nozzle 52 and an oil nozzle 53 that are sustained in proper relation to each other by a frame 54 to which said nozzles are clamped by a head 55 that is held firmly in place by a nut 56 threaded on the outer end of a stud 57 that is carried by the frame 54. The pipes which supply steam to the various sections of the burner are connected by unions 58 to the upper ends of the frames 54, and oil is supplied to the burner sections through tubes which are connected to the lower ends of the frames by unions 59. It will be understood that the bores of the bosses to which the unions 58 and 59 are applied communicate with the bores of the respective nozzles 52 and 53. This construction provides a simple and highly efficient oil burner of the injector type.

The burner section 50 constitutes what we may term the main burner, while sections 100 designated 60 and 61 constitute auxiliary burners. A branch 62 leads from the pipe 45 to a valve casing 63 (Figs. 3, 5, 6 and 8) and within the casing are two valves 65 and 66 which control the respective ports 67 and 68 105 that communicate through pipes 69 and 70 with the respective burner sections or auxiliary burners 60 and 61. Each of the valves 65 and 66 has a stem which is guided within a bore of the casing and depends a suitable 110 distance below the lower end of the casing, the stems being of different lengths, as shown in Fig. 5, for a purpose which will presently appear.

A branch 75 leads from the pipe 45 to a steam operated pump 76 which may be of any approved type, the one illustrated being a piston pump, and without going into detail in the description of its construction it may be briefly explained that a piston rod 77 extends from one end of the piston structure through the adjacent end wall of the pump casing where it is pivotally connected to a lever 78 that is fulcrumed at 79 to a bracket that is carried by the pump casing. Intermediate its ends the lever 78 has connected to it the valve operating rod 80. A pipe 81 leads from an oil supply tank 82 (that is shown in dotted lines as located below the floor on which the apparatus stands) to the inlet side 130

of the pump, and from the outlet side of the pump a pipe 83 leads to the bottom of an oil reservoir 84, shown in detail in Figs. 5, 6 and 7.

5 The oil reservoir 84 is shown as consisting of a box like casting having a transverse partition 85 which divides the interior of the reservoir into compartments 86 and 87. Formed within one of the lower corners of the compartment 87 is an elongated tubular boss 88 within which an overflow tube 90 has a sliding fit, the tube being provided a suitable distance upwardly from its lower end with an overflow opening or openings 91. In axial alignment with the boss 88 is an external boss 92 into which the upper end of a pipe 93 is threaded, said pipe leading to the fuel tank 82. The overflow tube 90 has a trombone connection with the pipe 93 as will be readily understood from the construction described. Suitably attached to one side of the overflow tube 90 is a rack 95 the lower portion of the rack being spaced from the tube to allow it to descend alongside the boss 88 when the tube is in its lowermost position. Cooperating with the rack 95 is a pinion 96 of suitable design which is secured to the inner end of a shaft 97 that is journaled in a bearing 98 shown as formed integral with a plate 99 that closes an opening in the side of the reservoir 84, the same being secured in place by screws 100. Outwardly beyond the bearing 98 and within the lower portion of a housing 101 a gear 102 is secured to the shaft 97, and journaled upon the shaft on opposite sides of the gear 102 are pawl carrying plates 103. Pivoted at 104 to the plates 103 are pawls 105, shown in detail in Figs. 13 and 14. The free ends of the pawls are turned laterally to provide portions 106 which are adapted to engage the teeth of the gear 102 when the pawls are swung upwardly from the stops 107 that are formed on the plates 103 and serve to sustain the pawls in normal position. The pawl carrying plates are, in turn, supported in normal position by adjustable stops that are constituted of screws 108, threaded through lugs 109 that are turned laterally from the upper corners of the plates, the screws being arranged to abut the side walls of the housing 101.

Enclosed within an enlarged upper portion of the housing 101 are solenoids 110 and 111, and the movable core sections 112 of the solenoids are connected, through links 113, to offset portions of the pawls 105. Consequently, when either of the solenoids is energized, it will first swing the corresponding pawl 105 into engagement with the teeth of the gear 102 and further movement of the core will elevate the corresponding pawl carrying plate 103, rotating it about the shaft 97, and with it, the gear 102 to impart like movement to the shaft to which the gear is secured. It will be remembered that the shaft 97 has

driving connection with the overflow tube 90 through the rack 95 and pinion 96. The top of the housing 101 is closed by a cover 115 that is secured to the upper end of the housing by screws 116. The fixed portions 112^a of the cores of the solenoids 110 and 111 are fastened to the cover 115 by screws 117. As a convenient means for manually adjusting the overflow tube 90, the shaft 97 is projected outwardly through an aperture in a face plate 118 which closes the open front of the lower portion of the housing 101, and at its outer end the shaft is equipped with a hand wheel 120. When the pawls 105 are in normal position, the shaft is free to be rotated by the hand wheel 120 and through the connections above described adjust the overflow tube 90. As will hereinafter appear there are circumstances under which it is desirable to raise the oil level in the reservoir 84 more quickly than would be accomplished by the automatic means provided for the purpose and involving the solenoids and mechanism associated therewith.

Carried by the upper end of the overflow tube 90, where it projects through an opening in the cover 122 which is removably secured to the upper end of the reservoir 84 by screws 123, is a button 125 that is arranged to engage the stems of valves 65 and 66. It will be noted that the stem of valve 65 is somewhat longer than the stem of valve 66 so that as the tube is elevated, the former valve will first be lifted from its seat and by continued movement of the tube the latter valve will be lifted and both valves held unseated.

The respective compartments 86 and 87 of the reservoir 84 have, adjacent the bottom of the reservoir, outlet openings 127 and 128, the former having connected to it a tube 129 which leads to a manifold 130 that has connection through the tubes 131 and 132 with the auxiliary burners 60 and 61. The outlet opening 123 of compartment 87 is connected through a tube 135 with the main burner 50. Inasmuch as oil is delivered from the pump 76 through the tube 83 directly to the compartment 86, the oil overflows therefrom into compartment 87, the compartment 86 thus being maintained full of oil and as a consequence thereof the oil level in the oil lines leading to the auxiliary burners 60 and 61 is maintained at its maximum height at all times. The oil level in compartment 87 is dependent upon the elevation of the overflow opening 91 of the tube 90, and inasmuch as the main burner is supplied with oil from this compartment, the level of oil in the oil line 135 leading to the main burner is variable.

The actuation of the solenoids 110 and 111 is controlled by a thermostat shown conventionally in the wiring diagram of Fig. 15. Sustained by a base 138 is a thermostatic ele-

ment 139 which carries a tongue 140. The free end of the tongue swings between adjustable contacts 142 and 143 on a plate 144 that is pivoted at 145 to the base. By swinging the plate 144 on its pivot, the contacts 142 and 143 may be shifted simultaneously and without disturbing their relative adjustment to cause the thermostat to act at different temperatures, accordingly as a pointer 146 on the plate 140 is set with respect to a scale 144 on the base. From a source 150 of electric energy represented conventionally as a battery, current is led through a conductor 151 to the thermostatic element 139 and tongue 140. If the tongue swings to the right, by reason of a rise in temperature affecting the thermostatic element 139, far enough to engage the contact 142, the flow of current continues on through a conductor 152 to the winding of solenoid 110 and thence through a branched conductor 153 to the ground. Upon the occasion of a drop in temperature sufficient to cause the tongue 140 to swing into engagement with contact 143, the current will be directed through a conductor 154 to the wiring of solenoid 111 from which it passes on through the conductor 153 to the ground. In order to produce reciprocations of the solenoid cores it is necessary 30 to intermittently close the circuit which energizes the solenoids, and to this end an intermittently acting switch of any approved type may be employed. In the present instance, a switch is provided that is intermittently 35 operated by the oil pump 76. This switch consists of a contact member 155 that is carried by the piston rod 77 and the same is arranged for engagement with a fixed contact member 156 that may be supported by, 40 but insulated from, the casing 3 of the apparatus. A conductor 157 leads from the source of electric energy or battery 150 to contact member 155 while contact member 156 is grounded through the pump casing and 45 a conductor 158.

Before proceeding with the description of the operation of the apparatus, it should be explained that the inner end of the damper 25 is connected, through a link 160, to the inner end of a lever 161 that is fulcrumed at 162 on a support 163 that is carried by an adjacent portion of the casing 3. While the section of the lever which is housed within the casing 3 is preferably formed of a casting, its outer end is constituted of rods 164 which extend through a suitable opening in the front of the casing. A weight 165 is adapted to be adjusted along the rods 164 to normally overbalance the damper 25, the 50 weight being adapted to be locked in any adjusted position by a set screw 166. Sustained by a bracket 170, with its axis a short distance inwardly of the fulcrum of the lever, is a bellows 171, and a thrust pin 172 is interposed between the free end of the bellows

and a depressed seat in the lever 161. The bellows 171 communicates, through a pipe 174, with the lower portion of the generator 28. Consequently, steam pressure within the generator is communicated to the bellows and 70 when such pressure becomes great enough to overcome the action of the weight 165 it will depress the lever and close the damper 25.

In considering the operation of the above described form of the invention, let it be 75 assumed that oil is present in the system, and that while it stands at maximum level in the auxiliary burners 60 and 61, that it is at a level in the main burner 50 determined by the position of the overflow opening 91 of the 80 tube 90. It will also be assumed that water is present within the generator 28. A quantity of oil is introduced into the preheating burner 6 through the spout 7 and is ignited through the opening that is normally closed 85 by the door 11. There being no steam pressure in the generator 28, the damper 25 is held open by the weight 165. This permits the flame from the preheating burner to sweep upwardly through the opening 18 and 90 it is deflected rearwardly by the damper 25 toward and about the generator 28. This causes steam to be generated which is conducted through pipes 44, 45 and 46 to the main burner 50, throwing said burner into 95 operation. As this burner continues in action, it supplies the heat for the generator 28 and as the steam pressure within the generator continues to rise the flame naturally increases. The higher steam pressure however, acts also through the bellows 171 to depress the damper and thus shield to a greater or lesser extent the generator from the heat of the flame. It is apparent that the opening 18 is in effect a by-pass for only a part 100 of the flame, the major portion of the flame at all times issuing through the combustion chamber 16 to the fire box *a'* of the furnace, and even when the damper 25 is open the portion escaping through the passageway 18 105 ultimately reaches the furnace through the upper portion of the opening *a*.

The thermostat 138 may be located in an apartment which is being heated by the furnace, or in an oven fired by the apparatus, or in any other place where it is under the influence of the heat created by the apparatus. In case the heat affecting the thermostat becomes great enough to cause the tongue 140 to engage the contact 142, a circuit will be 110 established through the path previously described including the winding of solenoid 110. Then, upon the intermittent engagement of the contact members 155 and 156, caused by the action of the pump 76, pulsations of current 115 will be directed through the solenoid to reciprocate its movable core section and consequently to rotate, in the manner already described, the shaft 97 and the pinion 96 in a 120 direction to feed the rack 95 and the overflow 125 130

tube 90 by which it is carried downwardly, thus lowering the oil level within the compartment 87 of the reservoir and consequently within the oil line leading to the main burner. As a result of this condition less oil is expelled from the burner and consequently the temperature of the flame drops which will have the effect of lowering the temperature which operates the thermostat. The tongue 140 will then withdraw from the contact 142 and the apparatus will continue to operate at the prevailing oil level until there is a possible drop in the temperature sufficient to cause tongue 40 to engage the contact 143. When this happens, the current is directed through conductor 154 to the winding of solenoid 111 and thence through the wire 153, the ground, the wire 158, the intermittent switch comprised of contact members 155 and 156, and the conductor 157 to the source or battery.

When solenoid 111 is thus energized, it acts, through the corresponding pawl 105 where-with it has connection, to rotate the shaft 97 in the opposite direction and elevate the tube 90 and cause a corresponding rise in the oil level within the oil line leading to the main burner.

Now let it be supposed that even when the oil level in the compartment 87 approaches its maximum height the temperature affecting the thermostat is not sufficiently high to retract the tongue 140 from the contact 143. Under such a condition as this it is necessary to throw into operation one or both of the auxiliary burners. This is accomplished by the engagement of the button 145 that is carried by the upper end of the overflow tube 90 with the stem of valve 65 and the lifting of the valve by the continued slight upward movement of the tube. As soon as the valve is open, steam rushes through the pipe 69 to the burner 60 and sets said burner in operation; and if the heat is still insufficient to cause the retraction of the tongue 140, the tube 90 will continue to rise and open the valve 66 and thus throw burner 61 into operation.

The burners will then continue to operate at their maximum capacity until there is a rise in temperature sufficient to swing the tongue 140 in engagement with the contact 141, energizing the solenoid 110 which is responsible for the lowering of the tube 90.

Fig. 16 represents diagrammatically a modification of our invention wherein the oil reservoir is moved bodily up and down to vary the oil level with respect to the burners.

175 represents a shaft which is suitably supported for oscillation and to which is fastened a ratchet 176 and a lever 177. The ratchet has reverse teeth on its opposite edges, and V notches across its top. The lever 177 carries an oil reservoir 180 at one end, and 65 a counterbalancing weight 181 at the other.

It also includes a depending arm 182 that is provided, on its lower edge, with cams 183 and 184.

A steam line 185 which is the equivalent of the steam line represented by pipes 44 and 45 of the previously described embodiment of the invention leads from the steam generator to a valve casing 186 containing valves 187 and 188 which are, respectively, equivalents of the valves 65 and 66, of the former embodiment. These valves control the admission of steam to pipes 189 and 190 which lead, respectively, to the auxiliary burners 191 and 192. The main burner 193 receives its supply of steam through a branch 194 of 70 the pipe 185. The stems of the valves 187 and 188 are shown as equipped with rollers for cooperation with the previously mentioned cams 183 and 184, respectively. Oil is delivered to the receptacle 180 through a pipe 195 from the oil pump; and excess oil delivered to the receptacle escapes through an overflow 196 that discharges into a drain pipe 197 leading to the oil tank. Oil is conveyed from the receptacle 180 to the main burner 193 through a pipe 200, and through a pipe 201 to a manifold 202 which supplies, through the tubes 203, the auxiliary burners 191 and 192.

The cores of solenoids 210 and 211, which are equivalents of the former solenoids 110 and 111, are connected, through links 212 with arms 213 that are journaled on the shaft 175 on opposite sides of the ratchet 176. Pawls 214, that are connected to these arms, 95 cooperate with the teeth that are formed on the opposite edges of the ratchet 176. The pawls are normally held out of the path of the teeth by suitably supported stationary stops 215.

When the solenoid 210 is energized it will lift the corresponding arm 213 and throw the pawl carried thereby into engagement with the ratchet 176, at the same time withdrawing a locking device 217 from engagement with the V notches of the ratchet thereby releasing the ratchet and the lever. This will cause a rotation of the ratchet, and consequently the lever, in a direction to elevate the reservoir 180 and raise the oil level in the oil lines of the burners. As the parts are shown in the diagram, the same movement of the lever 177 will result in engaging cam 183 with the stem of valve 187, depressing said valve and throwing into operation burner 191. Further movement of the lever in the same direction will result in unseating valve 188 and directing steam to the second auxiliary burner 192. Energization of the solenoid 211 will reverse the operation, cut out the auxiliary burners and lower the oil reservoir 180, continued movement in this direction beyond the position shown in the drawings, lowering the oil level in the main burner 120 and causing the heat of its flame to be reduced.

115
125
130

Through the modification illustrated in Fig. 17, we accomplish with one burner what has practically been accomplished with a plurality of burners in the foregoing forms of the invention. In the present modification the burner is designated 220, and it is supplied with steam from the generator 201 through the pipe 222. The burner is supplied with oil through the pipe 223 from a reservoir 225 that receives its oil from the pump through a pipe 226. The reservoir has an overflow 227 which returns the excess oil through pipes 228 and 229 to the oil tank. The reservoir 225 is equipped with a suitable number of ears 230 which are guided on rods 231 that rise from a base 232, and springs 233 surround said rods and are interposed between the ears 230 and nuts 234 that are carried by and adapted to be adjusted along the upper ends of the rods. These springs tend to lower the reservoir in opposition to a bellows 235 which supports the reservoir and rests upon the base 232 and communicates, through a pipe 236, with the steam generator 221.

A bellows 240 is connected through a branch 241 with the pipe 236 and tends, as in the first described form of the invention, to depress a lever 242 which has connection at its inner end, through a link 243, with the inner end of a damper 244 which controls the passage of a part of the products of combustion from the combustion chamber 245 through an opening 246 to the compartment enclosing the generator 221.

Supported upon the outer end of the lever 242 is electromagnetic mechanism 248 which may be identical with that disclosed in a pending application filed April 18th, 1925, by Marc Resek, one of the present applicants, and bearing Serial No. 24,052. This mechanism involves adjustable weights which are moved inwardly and outwardly with respect to the fulcrum of the lever 242 by solenoids which are under the control of a thermostat, precisely as the solenoids 110 and 111 are under the control of the thermostat shown in connection with the first described form of the present invention.

When this form of the invention is in operation, steam is conducted through the pipe 222 to the burner 220 to suck from the oil line 223 a quantity of oil depending upon, first, the steam pressure and, secondly, the level of the oil with respect to the burner.

By reference to the above mentioned application, it will be seen that when the temperature affecting the thermostat falls, it will shift the center of gravity of the mechanism 248 outwardly with respect to the fulcrum of the lever 242 and this will tend to lift the damper 244 so as to enlarge the opening for the products of combustion passing from the combustion chamber to the generator and this will result in increasing the steam pressure within

the generator, which steam pressure will be communicated through the pipes 236 and 241 to the bellows 240 and 235. The former bellows will tend to depress the lever and move the damper toward closed position; while the latter bellows will tend to elevate the oil reservoir 225 and thus raise the oil level with respect to the burner. As a consequence of this action, greater steam pressure and a freer supply of oil will be delivered to the burner so that the flame of the burner increases. The steam pressure and oil level will continue to rise so long as the center of gravity of the weight mechanism 248 is moved outwardly, and upon the reversal of the conditions responsible for the shifting of said weight, the center of gravity of said mechanism 248 will be moved inwardly, and both the steam pressure and the oil level will be lowered.

This embodiment of the invention, therefore, provides a much wider range of adjustment for a single burner than is afforded by the former modifications, rendering the auxiliary burners unnecessary.

Having thus described our invention, what we claim is:

1. In oil burning apparatus, the combination of a burner of the injector type, a steam generator subjected to the heat of the burner flame, pressure actuated means operated by steam from the generator for maintaining the pressure therein substantially constant, a conduit leading from the steam generator to the burner, an oil tank, an oil reservoir having an overflow that drains into said tank, a pump operated by steam from the generator for pumping oil from the tank to the reservoir, and thermostatically controlled means subjected to the heat produced by the apparatus for changing the relation between the burner and the oil level in the reservoir.

2. In oil burning apparatus, the combination of a main burner and an auxiliary burner, said burners being of the injector type, a source of pressure fluid, conduits leading from said source to the burners, the conduit leading to the auxiliary burner having a valve, an oil reservoir, means for supplying said reservoir with oil in amount equal to or in excess of the maximum demand of the burners, and means for changing the relation between the main burner and the oil level of the reservoir and through which means the aforesaid valve is opened when the oil level reaches a predetermined height with respect to the main burner.

3. In oil burning apparatus, the combination of a main burner and an auxiliary burner, said burners being of the injector type, a steam generator subjected to a source of heat, conduits leading from the generator to the burners, the conduit leading to the auxiliary burner having a valve, an oil reservoir, means for supplying said reservoir with oil in amount equal to or in excess of the maximum

5 demand of the burners, the reservoir having an overflow, means for changing the height of the overflow with respect to the burners, and connections through which the aforesaid valve is opened when the overflow reaches a predetermined height.

10 4. In oil burning apparatus, the combination of a main burner and an auxiliary burner, said burners being of the injector type, a steam generator subjected to a source of heat, conduits leading from the generator to the burners, the conduit leading to the auxiliary burner having a valve, an oil reservoir, means for supplying said reservoir with oil in 15 amount equal to or in excess of the maximum demand of the burners, the reservoir having an overflow, means affected by the heat produced by the burners for automatically changing the height of the overflow with respect to 20 the burners, and connections through which the aforesaid valve is opened when the overflow reaches a predetermined elevation.

25 5. In oil burning apparatus, the combination of a main burner and an auxiliary burner, said burners being of the injector type, a steam generator subjected to a source of heat, conduits leading from the generator to the burners, the conduit leading to the auxiliary burner having a valve, an oil reservoir, means 30 for supplying said reservoir with oil in amount equal to or in excess of the maximum demand of the burners, the reservoir having an overflow, and means responsive to changes in temperature for varying the height of the 35 overflow with respect to the burners and for opening the aforesaid valve when the said overflow attains a predetermined elevation.

40 6. In oil burning apparatus, the combination of a main burner and an auxiliary burner, said burners being of the injector type, a source of pressure fluid, conduits leading from said source to said burners, a valve in the conduit leading to the auxiliary burner, an oil reservoir, means for supplying oil to the 45 reservoir in amount equal to or in excess of the maximum demand of the burners, the reservoir having an overflow, and means for changing the height of the overflow with respect to the burners and for opening the aforesaid valve when the overflow attains a predetermined height.

50 7. In oil burning apparatus, the combination of a main burner and a plurality of auxiliary burners, said burners being of the injector type, a source of pressure fluid, conduits leading from said source to said burners, valves in the conduits, leading to the auxiliary burners, an oil reservoir, means for supplying oil to the reservoir in amount equal 55 to or in excess of the maximum demand of the burners, the reservoir having an overflow, and means affected by the heat produced by the apparatus for changing the height of the overflow with respect to the burners and 60 for opening the aforesaid valves successively

when the overflow attains predetermined heights.

65 8. In oil burning apparatus, the combination of a burner of the injector type, a steam generator supported in operative relation to the burner, a conduit leading from the generator to the burner, means responsive to the steam pressure within the generator for governing the amount of heat delivered to the generator, an oil reservoir having an overflow, and means responsive to temperature changes and subjected to heat produced by the apparatus for varying the height of the overflow with respect to the burner. 75

70 9. In oil burning apparatus, the combination of a burner of the injector type, a steam generator for supplying steam thereto and situated in operative relation to the burner, means responsive to the steam pressure in the generator for maintaining the pressure substantially constant, an oil reservoir, a conduit leading from the reservoir to the burner, the reservoir having an overflow, and means responsive to temperature changes for varying the height of the overflow with respect to the burner. 90

75 10. In oil burning apparatus, the combination of a burner of the injector type, a steam generator for supplying steam thereto and situated in operative relation to the burner, means responsive to the steam pressure in the generator for maintaining the pressure substantially constant, an oil reservoir, a conduit leading from the reservoir to the burner, and means responsive to temperature changes for varying the oil level in the reservoir thereby to regulate the burner flame. 100

80 11. In oil burning apparatus, the combination of a burner of the injector type, a source of pressure fluid, a conduit leading from said source to the burner, an oil reservoir, a conduit leading from the oil reservoir to the burner, said reservoir having an overflow, mechanism that is operable in one direction to elevate the overflow and in another direction to lower the overflow with respect to the burner, electromagnetic means for operating said mechanism in each of the aforesaid directions, a source of electric current, a branched circuit including said source, each branch including one of the said electromagnetic means, a thermostatic switch in said circuit for selecting one of the other of said branches, and an intermittently acting switch in the circuit. 110

85 12. In oil burning apparatus, the combination of a main burner and an auxiliary burner, both burners being of the injector type, a source of pressure fluid, conduits leading from said source to said burners, a valve included in the conduit leading to the auxiliary burner, an oil reservoir, a conduit leading from said reservoir to the burner, means for delivering oil to the reservoir in amount equal 90 to or in excess of the maximum demand of the burner, and means responsive to the temperature of the reservoir for varying the height of the overflow with respect to the burner. 125

burners, means for vertically adjusting the overflow, and connections through which the aforesaid valve is opened when the overflow has attained a predetermined elevation.

5 13. In oil burning apparatus, the combination of a main burner and an auxiliary burner, both burners being of the injector type, a source of pressure fluid, conduits leading from said source to said burners, a valve included in the conduit leading to the auxiliary burner, an oil reservoir, a conduit leading from said reservoir to the burner, means for delivering oil to the reservoir in amount equal to or in excess of the maximum demand of 10 the burners, means responsive to temperature changes and subjected to the heat produced by the apparatus for vertically adjusting the overflow, and connections through which the aforesaid valve is opened when the over- 15 flow has attained a predetermined elevation.

14. In oil burning apparatus, the combination of a main burner and an auxiliary burner, both burners being of the injector type, a source of pressure fluid, conduits leading from said source to said burners, a valve in the conduit leading to the auxiliary burner, an oil reservoir having two compartments, means for delivering oil to the first of said compartments and from which compartment 25 the oil overflows into the second compartment, the second compartment having a vertically adjustable overflow, a conduit leading from the first of said compartments to the auxiliary burner, a conduit leading from the 30 second of said compartments to the main burner, means for vertically adjusting the overflow, and connections through which the aforesaid valve is opened when said overflow has attained a predetermined elevation.

40 15. In oil burning apparatus, the combination of a main burner and an auxiliary burner, both burners being of the injector type, a steam generator situated in operative relation to the burner, means responsive to the 45 steam pressure in the generator for governing the amount of heat delivered to the generator, conduits leading from the steam generator

to the burners, a valve in the conduit leading to the auxiliary burner, an oil reservoir having two compartments, an oil tank, a pump 50 operated by steam from the generator for pumping oil from the tank to the first compartment of the reservoir, the said first compartment overflowing into the second compartment, a vertically adjustable overflow for 55 the second compartment which discharges into the tank, a conduit leading from the first compartment to the auxiliary burner, a conduit leading from the second compartment to the main burner, means responsive to 60 temperature changes and subjected to the heat produced by the apparatus for raising and lowering the said overflow, and connections through which the aforesaid valve is opened when the overflow has attained a given elevation. 65

16. In oil burning apparatus, the combination of a burner of the injector type, a steam generator subjected to a source of heat, means for maintaining a substantially constant steam 70 pressure in the generator, a conduit leading from the steam generator to the burner, an oil reservoir, a conduit leading from the reservoir to the burner, and thermostatic means subjected to the heat produced by the apparatus for automatically varying the oil level 75 of the reservoir with respect to the burner.

17. In oil burning apparatus, the combination of a steam generator subjected to a source of heat, an oil burner of the injector type, a conduit leading from the steam generator to the burner, an oil reservoir, a conduit leading from said reservoir to the burner, means for varying the steam pressure in the generator, and means operated by the variable 80 pressure in the generator for raising the oil level of the reservoir with respect to the burner as the steam pressure within the generator increases. 85

In testimony whereof, we hereunto affix our signatures. 90
